UNITED STATES PATENT OFFICE

2,532,090

REFRIGERATOR FOR AUTOMOBILES AND
MOTOR BOATS

Jerome J. Dubuc, Burlington, Vt.

Application January 29, 1946, Serial No. 644,020

1 Claim. (Cl. 62—116)

1

This invention relates to an electrical refrigerator for automobiles and motor boats, and one of its objects is to provide a refrigerator which can be operated from the six or twelve volt electrical system of the automobile or motor boat, to keep small quantities of luncheon food, fresh caught fish or small game animals, and beverages at a low temperature, without imposing an excessive burden on the storage batteries and current generator of the system.

With the above and other objects in view, the invention comprises certain new and useful constructions, combinations, and arrangements of parts, clearly described in the following specification, and fully illustrated in the accompanying drawings, in which:

Fig. 1 is a front elevation.

Fig. 2 is a vertical sectional view.

Fig. 3 is a vertical sectional view, taken on line 3—3 of Fig. 1, looking in the direction of the arrows.

Fig. 4 is a front elevation of an instrument board, broken away, to illustrate one form of installation of the improved refrigerator.

Fig. 5 is a plan view of a circuit layout.

Referring to the accompanying drawings, which illustrate the practical embodiment of the invention, 5 designates a metal back wall and 6 a front metal frame, which is connected to the inner metal compartment forming body 7, by the flange 8. A body wall 9 is connected by its front and rear flanges 10 and 11, respectively, to the front metal frame 6 and to the back wall 5.

Within the body 7, which is in the nature of an interior box-like structure, a back wall 12 is secured to the rear flanges 13 of the body 7. A shelf 14 is mounted on the side walls 7a and 7b of the body 7, and on this shelf a freezing cabinet or case 15 is provided. A tray holding slide or drawer 16 is arranged to move into and out of the cabinet or case 15.

Between the inner back wall 12 and the outer back wall 5, a refrigerating compressor 17 is mounted, and this compressor is operated by means of the electrical motor 18, through the flexible belt drive 19. This electrical motor is of the six volt or twelve volt type, and is designed to operate from the same electrical current supply system as the starter and ignition of the automobile or motor boat operates.

The cooling coil 20 extends from the compressor unit into the freezer case or cabinet 15,

2

and an additional freezer coil 21 may be provided in the insulation 22, at the bottom of the interior body 7. Suitable insulation 23 is arranged between the sides of the body 7 and the sides of the outer case of the refrigerator.

A door 24 is secured by the hinges 25 to the front frame 6, and is provided with a hand operated latch 26 to engage the keeper 27, which is attached to one side of the frame 6. A temperature regulator 28 is attached to the lower front side of the frame 6.

The entire cabinet or refrigerator is attached to the instrument board of the automobile or motor boat, or installed in any other suitable position, so that it will occupy little space and will always be within easy access. It may also be installed in any other suitable position in the automobile or motor boat.

The electrical motor 18 is automatically controlled by means of the thermostat 29, so that it operates only intermittently, and will not be a constant drain on the current supply system of the automobile or motor boat. The refrigerator may be installed in the rear end of the automobile, 25 under the trunk compartment hood.

The refrigerator may be constructed in any required shape. It is to be constructed with a reduced capacity of one or one and one-half cubic feet. It may also be installed directly under the 30 panel which carries the instrument board. It will provide a greatly needed service for automobile or road trailers. It is thought that the temperature condition to be established and maintained in the refrigerator should be about 35 forty degrees, but a higher or lower temperature setting may be provided, if required.

It is understood that various changes in the details of construction, the means for control and installation, may be made, within the limits 40 of the invention, as defined by the claim hereof.

Having described the invention, I claim as new:

A refrigerator adapted for use in small spaces comprising an outer and an inner compartment, said outer compartment having a rear wall, top, 45 bottom and two side walls, the latter four walls having flanges at their front and rear ends, said rear flanges being adapted for connection with the rear wall, said inner compartment having a rear wall disposed at a predetermined distance 50 and parallel to said rear wall of the outer compartment and top, bottom and two side walls, the latter four walls having at their front an up-

wardly bent flange and at their rear an inwardly bent flange, the outwardly bent flange of the last mentioned four walls engaging the front flanges of the first stated four walls, insulation means disposed between the said respective four walls of the inner and outer compartment and an insulation layer outside of the rear wall of the inner compartment, a liquifying unit disposed between the outer and inner rear wall, an insulated door closing the front opening of the inner compartment, a food compartment disposed in said inner compartment, and a cooling unit extending from the liquifying unit into said food compartment and an additional cooling coil disposed within the insulation between the walls of the inner and outer compartment.
